TOY RAILROAD TURNTABLE

Robert I. Genin, New Rochelle, and Leon S. Wirch,
Forest Hills, N.Y., assignors to Child Guidance Toys,
Inc., Bronx, N.Y., a corporation of New York

Filed May 25, 1961, Ser. No. 65,343

Term of patent 14 years

(Cl. D34—15)

FIG. 1.

FIG. 2.

FIG. 3.

FIGURE 1 is a top plan view of a toy railroad turntable embodying the new design,

FIG. 2 is a side elevational view, and

FIG. 3 is a right end elevational view thereof.

We claim:

The ornamental design for a toy railroad turntable, substantially as shown.
